HENRY STANBRIDGE, OF TINSLEY, NEAR SHEFFIELD, ENGLAND, ASSIGNOR TO
JOSEPH ALBERT HILL, OF SHEFFIELD, ENGLAND.

PROJECTILE FOR ORDNANCE.

1,029,517.

Specification of Letters Patent. Patented June 11, 1912.

Application filed February 25, 1911. Serial No. 610,821.

To all whom it may concern:

Be it known that I, HENRY STANBRIDGE, subject of the King of Great Britain and Ireland, residing at 39 Rotherham road, 5 Tinsley, near Sheffield, England, engineer, have invented certain new and useful Improvements in and Relating to Projectiles for Ordnance, for which I have applied for Letters Patent in Great Britain, No. 4,253, 10 February 21, 1910, of which the following is a specification, reference being had to the accompanying drawings.

My invention has reference to the class of projectiles as described in British specifications No. 16707 of 1904 and No. 3033 of 15 1905 and has for object to improve the flight and also the interior of such projectiles. The hollowing of the head and consequent displacement of metal necessitates a 20 long radius for the ogive that forms the continuation of the parallel walls of such projectiles; as a consequence they compare unfavorably as regards steadiness of flight with shells having a shorter radius for the 25 ogive and a flat base. I therefore reduce in length and slope the parallel walls toward the base and while retaining a flat base considerably diminish the area thereof. The driving band is in consequence put 30 much farther forward, the proportion of slope at rear, parallel and forward slope depending on the length of shell, this in turn depending on the capacity. This design allows the air to close in behind the 35 projectile when in flight an advantage over projectiles with bases at right angles to the walls, and also assists to steady it; further, the weight of base is reduced. The base plug marked B, in accompanying drawing 40 has in consequence to be modified, the block which is inserted being shaped as follows: It has a central hole (b^3) with fuse threads and lips inward (b^2) and outward (b^1) or only outward and at an angle to conform to 45 the curvature or slope (a^2) of the base of the shell, also a projecting flange (b^4) to stop it from being pushed in the shell on firing.

The walls of the shell may be reduced at 50 the base, so that the closing in, similar to that described in No. 3033 of 1905, may be facilitated and even done cold and shaped as described in specification No. 5363 of

1881, Figure 2. Further to prevent the heat on penetration from igniting the bursting charge, also to economize space, I combine with a non-conducting liner such as asbestos marked C, in accompanying drawing and shaped to fit the interior of the shell, a non-corrosive metal liner D, to keep the liner C, firmly against the walls. This metal liner D, serves also to prevent the powder being ignited prematurely should a live shell break up in store. In the case of screw base shell, the said combined liners 65 are easily inserted; in the case of shells with solid bases I claim to put the same in before closing down the walls of the shell.

My invention is illustrated by the annexed drawings in which:—

Fig. 1, shows a section of the shell as above, with inserted base. Fig. 2, shows a section of a shell with the walls closed in on the interior lining.

Like letters and figures indicate similar 75 parts.

A, is the shell body. a^1 the concaved head. a^2 the slope of the base. B, the base plug. b^1 the outward obturating lips. b^2 the inward obturating lips. b^3 the fuse 80 hole and threads. b^4 the flange to stop the base being pushed into the shell on firing. C, the liner of non-conducting material. D, the non-corrosive metal liner, forming the powder chamber. 85

Having now particularly described my said invention, and in what manner the same is to be performed, I declare that what I claim, is:—

1. A projectile for ordnance comprising 90 a hollow shell having in combination a concave head, a tapering front portion having a long radius of ogive and an inwardly sloping base portion.

2. A projectile for ordnance comprising 95 a hollow shell having in combination a concave head, a tapering front portion having a long radius of ogive and an inwardly sloping base portion, a non-corrosive metal liner forming a chamber for the charge and 100 a liner of non-conducting material held in place by said metal liner.

3. A projectile for ordnance comprising 105 a hollow shell having in combination a concave head, a tapering front portion having a long radius of ogive and an inwardly

sloping base portion, an open-ended non-corrosive metal liner forming a chamber for the charge and an open-ended liner of non-conducting material held in place by said 5 metal liner, the walls of the shell and the liners being subsequently closed in toward one another.

In witness whereof I have hereunto set my hand in presence of two witnesses.

HENRY STANBRIDGE.
